UNITED STATES PATENT OFFICE.

HENRY D'OLIER, JR., OF PHILADELPHIA, PENNSYLVANIA.

DETACHABLE INCANDESCENT-LAMP SHADE.

No. 836,490.

Specification of Letters Patent.

Patented Nov. 20, 1906.

Application filed September 21, 1905, Serial No. 279,562.

To all whom it may concern:

Be it known that I, HENRY D'OLIER, Jr., a citizen of the United States, residing in the city of Philadelphia, in the county of Philadelphia and State of Pennsylvania, have invented a new and useful Improvement in Detachable Incandescent-Lamp Shades, of which the following is a specification.

My invention relates to means for cheaply and effectively applying to an incandescent-lamp socket a shade or reflector which shall be capable of rotation about the axis of the lamp-socket or of the lamp for the purpose of directing the rays of light in desired directions.

To this end I may employ a reflector or shade made of sheet material, preferably steel or brass, perforated with an aperture large enough to enable it to pass over the end of a lamp-socket. An independent resilient ring member, made, preferably, of sheet-brass, is adapted to spring over the lamp-socket and retain the shade or reflector against a shoulder on the socket, or the resilient ring member may be sprung into the aperture in the sheet-metal shade or reflector and the ring then sprung over the lamp-socket, preferably engaging a bead thereon.

My invention resides in other features hereinafter described, and pointed out in the claims.

For an illustration of some of the forms my invention may take reference is to be had to the accompanying drawings, in which—

Figure 1 is a vertical elevational view of a lamp and socket, the reflector or shade and resilient ring member being shown in vertical section, the ring member embracing a bead on the lamp-socket. Fig. 2 is a view similar to Fig. 1, except that the shade or reflector is confined between a shoulder on the lamp-socket and the resilient ring member. Fig. 3 is a perspective view of the resilient ring member. Fig. 4 is a vertical sectional view of a resilient ring member and a shade, an extension member intervening between them.

Referring to Fig. 1, S is a standard incandescent-lamp socket having the usual key K and supporting an incandescent lamp L. At s the socket S is reduced in diameter, thus forming a shoulder a. Upon the portion s is the usual bead b. A resilient ring member R (shown in perspective in Fig. 3) has a bead c, which registers with the bead b on the socket S. A flange f is provided upon the ring member R, and between the flange f and

the bead c is confined the shade or reflector A. The resilient ring member R is split or incomplete circumferentially, as indicated at g in Fig. 3. A hole or aperture of suitable size is punched in the shade or reflector A, and the resilient ring member R is sprung into it until the reflector A is confined between the flange f and the bead c. Then the ring member R is sprung over the bead b until the beads b and c register with each other. When in this position, the reflector A is rotatable upon the ring member R to any position around the axis of the lamp and socket, the aperture or hole in the shade A being sufficiently large to permit easy motion.

As shown in Fig. 1, the reflector or shade A is practically a surface of revolution whose axis is in the line X X at an angle of forty-five degrees with the axis of the socket or lamp. By rotating the shade A on the ring R light may be directed in desired directions. By perforating the shade or reflector A at different angles to its axis light may be thrown to other desired directions.

In Fig. 2 the parts are the same as those described in connection with Fig. 1. The arrangement is different, however, in that the shade or reflector A is passed over the socket end and placed against the shoulder a, where it is confined by the flange f of the ring R, which embraces the portion s of the socket and rests upon the socket-bead b. In Fig. 2, however, the aperture is at an angle only of thirty degrees with the axis of the shade A.

In Fig. 4 the shade A has an aperture larger than in the arrangements of Figs. 1 and 2. B is an extension member or cylinder of sheet metal having spun in it a bead k near its lower end of larger diameter. A flange m is spun over the edge of the aperture great enough to permit the easy rotation of the reflector A confined between the bead k and the flange m. The shell or extension B tapers toward its upper end, where it is turned in at n. The aperture thus formed at the upper end of member B is adapted to receive the resilient ring member R. (Shown in Fig. 3.) The ring member R may be sprung over a socket S until the socket-bead registers with the ring-bead c. The effect is to bring the lamp filament nearer to the shade or reflector A than by the arrangements shown in Figs. 1 and 2.

From the foregoing description it is apparent that a shade or reflector of sheet material having a simple non-reinforced aperture

may be quickly, efficiently, and cheaply applied to an incandescent lamp and its socket in such fashion as to permit its rotation in order to throw light in desired directions.

5. It is apparent that no riveting, soldering, or other permanent fastenings are necessary, the simple resilient independent ring member R serving to attach the shade to the lamp-socket.

10. This construction is exceedingly cheap, simple, efficient, and satisfactory in operation.

Obviously the lamp-socket may be rigidly supported in any suitable manner, or it may 15 hang by the usual incandescent-lamp cord.

What I claim is—

1. In combination, an incandescent-lamp socket, a shade or reflector member, an aperture in said shade or reflector member adapted to embrace said socket, the axis of the lamp-socket being at an angle with the axis of said shade or reflector member, and a single independent resilient ring member adapted to confine said shade or reflector member 25 upon said socket and to permit the rotation of said shade or reflector member.

2. In combination, a lamp-socket, a shade or reflector, an aperture in said shade or reflector, the axis of the lamp-socket being at 30 an angle with the axis of the shade or reflector, and a single resilient ring member adapted to expand in said aperture to rotatably secure said shade or reflector upon said socket.

35. 3. In combination, a lamp-socket, a bead thereon, a shade or reflector, an aperture in said shade or reflector, the axis of the lamp-socket being at an angle with the axis of said shade or reflector, a single resilient ring member adapted to expand in said aperture, and a bead on said ring member adapted to register with said socket-bead.

40. 4. In combination, an incandescent-lamp socket, a bead thereon, a rotatable shade or reflector having an aperture, a single resilient ring member adapted to expand in said aperture,

ture, and a bead on said ring member adapted to register with said socket-bead.

5. In combination, an incandescent-lamp socket, a bead thereon, a rotatable shade or reflector having an aperture, a single independent resilient ring member, a flange and a bead on said ring member, said ring member being adapted to expand in said aperture to confine said shade between said bead and 55 said flange, and said bead adapted to register with said socket-bead.

6. In combination, a shade or reflector made of sheet material and having an aperture and a single independent resilient ring member adapted to expand in said aperture to rotatably secure said shade or reflector. 60

7. In combination, a sheet-metal shade or reflector having an aperture, and a single independent resilient split-ring member adapted to expand in said aperture to rotatably support said shade or reflector. 65

8. In combination, a lamp-socket, a shade or reflector, and means for supporting said shade or reflector upon said socket comprising a single independent resilient ring member, and a flange and a bead on said ring member, said ring member being adapted to expand in an aperture in said shade or reflector to confine the same between said flange 70 and bead.

9. The combination with a lamp-socket, of a shade or reflector member, an aperture in said shade or reflector member, adapted to embrace said socket, and a single independent resilient ring member adapted to confine said shade or reflector member upon said socket and to permit the rotation of said shade or reflector member. 75

In testimony whereof I have hereunto affixed my signature in the presence of two 80 subscribing witnesses.

HENRY D'OLIER, JR.
